(57) **CLAIM**

The ornamental design for a check in counter, as shown and described.

DESCRIPTION

FIG. 1 illustrates a front view of a check in counter employing an ornamental design in accordance with the present invention;

FIG. 2 illustrates a rear view of the check in counter of FIG. 1;

FIG. 3 illustrates a left side view of the check in counter of FIG. 1;

FIG. 4 illustrates a right side view of the check in counter of FIG. 1;

FIG. 5 illustrates a top plan view of the check in counter of FIG. 1;

FIG. 6 illustrates a front left perspective view of the check in counter of FIG. 1; and,

FIG. 7 illustrates a front right perspective view of the check in counter of FIG. 1.

The broken lines show portions of the check in counter that form no part of the claimed design.
